CONSOLIDATED ASHCROFT HANCOCK COMPANY, OF NEW YORK, N. Y., A CORPORA-
TION OF DELAWARE

SPEED RESPONSIVE APPLIANCE

Application filed May 15, 1930. Serial No. 452,697.

This invention relates to speed responsive devices, and more particularly to speed responsive devices actuated by centrifugal movement of a rotating mass. While in its broader aspects the invention is applicable to and useful in speed responsive devices or apparatus having other purposes, its most appropriate application is found in speed regulating and measuring instruments, for example, instruments known as tachometers, and the invention is hereinafter described, by way of example, as embodied in such an instrument.

The primary requisite in all such devices or instruments is that they shall respond with accuracy and delicacy to variations in speed, but it is further obvious that such devices, to be of commercial and practical value, must be strong, rugged, durable, and of simple construction, and such that manufacturing cost and upkeep shall be low.

In the attainment of the above and other desirable characteristics, the present invention provides a construction in which the number of pivoted joints (which always tend to wear and produce lost motion with resulting inaccuracy) is substantially reduced as compared with usual instruments of this type; it provides for transmitting motion of the actuating centrifugal mass to a movably responsive part (for example an index cooperating with a graduated dial) in response to successive equal increments or decrements of speed in such a way that for each equal increment or decrement of speed the responsive part shall move a uniform distance; it further provides for transmitting motion from the centrifugal mass to the responsive part or member by means which is adapted to absorb and substantially eliminate vibrations or oscillations of small amplitude, thereby reducing wear and increasing the accuracy of operation; and it further provides means for limiting the movement of the centrifugal mass to avoid damage through overspeed, or oscillation at low speeds when the mass is rotated in a substantially vertical plane.

Other objects and advantages of the invention will appear from the following explanation of a specific instance of the invention

shown, by way of example only, in the accompanying drawings.

In the drawings:

Fig. 1 is a front elevation, partly in section, of speed-responsive mechanism embodying the invention;

Fig. 2 is a front elevation, to larger scale, of the rotating weight-driving member and centrifugally actuated weights associated therewith;

Fig. 3 is a bottom view, partly in section, of the rotating weight-driving member and the weights;

Fig. 3a is an elevation of the centrifugally actuated weights and reciprocating head, showing their respective positions at different velocities;

Fig. 4 is a plan view of the speed responsive device of Fig. 1, showing the means for transmitting movement from the rotating and reciprocating upper head of the device to a suitable motion-responsive mechanism;

Fig. 5 is a fragmentary front elevation illustrating the application of the invention to an instrument comprising a dial, motion-responsive means in the form of an indicating pointer, index, or needle to which motion is transmitted, by means comprising a segment gear, from the upper rotating and reciprocating head of the speed-responsive mechanism of Fig. 1;

Fig. 6 is a section on the line 6—6 of Fig. 5, and

Fig. 7 is a section on the line 7—7 of Fig. 5.

The illustrated embodiment of the invention comprises a rotating weight-driving member 11 which is carried by a rotary shaft 12 turning in ball bearings 13 and 14, supported by a suitable framework 17. The rotating weight-driving member 11 carries a movable mass, (here shown as comprising the two pivoted weights 20 and 21), movable inwardly and outwardly to rotate in various orbital paths determined by the effect of centrifugal force. We prefer to connect the two weights pivotally to the rotating weight-driving member, preferably adjacent to the lower ends of the weights, as shown in Figs. 1 and 2.

The weight-driving member 11 preferably

extends but slightly to either side of its axis of rotation and is bifurcated, as shown in Fig. 3, to provide recesses 22 and 23 for receiving the weights 20 and 21 which normally extend therefrom generally parallel to the axis of rotation of the weight-driving member. The weight-driving member 11 preferably is located quite close to the bearing 14, as shown in Fig. 1 so as to diminish overhang and attendant likelihood of vibration.

Referring to the right-hand side of Fig. 3, the weight-driving member has spaced arms 27 and 28 through which a pin 29 is secured. The weight 21 shown in Fig. 3 has a transverse bore of larger diameter than pin 29. Bushings 30 and 31 are fitted into opposite ends of the bore, and these bushings have heads disposed between the opposed arms 27 and 28 respectively and the weight 21. In this way lost motion, both axially and laterally of the bearing pin 29, is prevented and the weight is constrained to pure rotation with respect to the pin, so that the path of the weights is determined solely by the speed of rotation of the weight-driving member (with its attendant centrifugal effect) and the effect of a suitable resilient member opposing the outward movement of the weights as hereinafter described.

In order to limit the outward movement of the weights under the action of centrifugal force, we provide the shorter part of each of the weights, that is the part depending below the pivot pin 29 in the illustrated embodiment, with a short extension indicated at 35 in Figs. 1, 2 and 3, and provide a suitable stop, preferably associated with the member 11 and conveniently in the form of a washer 37 joined to the weight-driving member 11 in any suitable manner and disposed in the inward path of these short extensions 35 of the weights. In this way outward movement of the longer upper part of the weight is checked by the engagement of the short extension 35 with this washer 37.

When a centrifugally actuated speed responsive device is disposed with its axis of rotation in a horizontal plane, or other than a vertical position, the effect of gravity upon the rotating weights at low speeds of rotation is likely to cause undesirable oscillations of the weights and consequently of the indicating or motion-responsive mechanism connected thereto. Accordingly, we provide means for checking the movement of the weights toward their axis of rotation at low speeds thus to prevent these undesirable oscillations. In the illustrated embodiment we have disposed the inner upper edges 40 and 41 of the two recessed sides of the weight-driving member 11 in the path of the inward movement of the upper longer portions of the weights, as shown in Fig. 2, so as to check movement when the weights toward the axis

of rotation of the device is disposed horizontally.

To utilize the centrifugal movement of the weights, and in the present embodiment to facilitate transmitting a desired component of the centrifugally induced movement of the weights to a motion responsive part, we provide a head, indicated generally at 50 (Fig. 1), (this head in this instance constituting an intermediate or primary responsive part). A spindle 15 of reduced diameter is slidably mounted within the spindle 15^a which is rigidly secured in any suitable manner to the weight driving member 11, the spindles 15 and 15^a being coaxial with the bearings 13—14 and the ball bearing member 16 in which the upper end of the spindle 15 is journaled. The head 50 is fast to spindle 15 which has a free axial movement in bearing 16 and in a bearing 16^a disposed within the spindle 15^a. Downward movement of this reciprocating head member 50 and spindle 15 is opposed by suitable means, for example a calibrated coil spring 51 disposed between the weight-driving member 11 and the movable head member 50. This spring also exerts an upward thrust against the movable head member 50 which, through connections about to be described opposes the outward swinging of the weights 20 and 21.

We prefer to reduce as much as possible the number of pivotal joints and connections between the weights and parts moved thereby in order to reduce wear of parts and consequent inaccuracy of operation. To this end we prefer to connect the weights to the movable head member 50 by flexible tension members 52 (Fig. 1) which may be, for example, thin pieces of metal, referred to hereinafter as "flexible strips". These flexible strips by reason of their flexibility, may be rigidly attached at their ends to the weights 20 and 21, and to the movable head member 50, without the use of pivotal connections. As shown in Fig. 1, the flexible strips are rigidly clamped to the weights adjacent to the pivotal axes thereof by washers 55 suitably held against the strips by screws 56, and at their opposite ends to the movable head member 50 in a similar manner by members 60, which may serve also to guide the flexible strip as hereinafter explained. In this way the use of pivotal connections between the weights and the movable head operated thereby is avoided.

In a device of this kind, wherein the motion of a weight in one direction is transmitted to a reciprocating or sliding head member restrained to motion in a non-parallel direction, the tension member (herein the flexible strip) connecting the weight and the reciprocating head necessarily moves through various angular positions with respect to its connected weight and reciprocating head. Since the flexible strip is rigidly affixed at its

opposite ends to the weight and to the reciprocating head, it is desirable, in order to prevent abrupt flexure and straining of the strip at these points of connection, to provide suitable strip-guiding surfaces, on the weight and reciprocating head, respectively, to cause the opposite ends of the strip to conform to gentle curves rather than abrupt bends. To this end we prefer to provide the 5 centrifugally actuated weights with cam faces which contact with the flexible strips, each cam face being, at least in part, in the form of a curve of sufficient radius to prevent abrupt bends in the flexible strips. As 10 shown in Fig. 1, the upper and outer cam surfaces of the two weights 20 and 21 curve inwardly as indicated at 59 so as to contact progressively with the associated flexible strips upon outward movement of the 15 weights. In like manner we prefer to provide the two upper strip-guiding members 60 (which preferably form a part of the reciprocating head 50 and clamp the flexible strips thereto) with cam faces, each in the 20 form of a gentle curve so that progressive outward movement of the lower ends of the flexible strips causes these strips progressively 25 to contact with the curved surfaces of these upper strip-guiding members and thus prevents abrupt bends in the strips adjacent the reciprocating head.

Normally the component of the motion of the centrifugally actuated weight transmitted through a connecting member to another 30 movable member will be a trigonometric function of the variable angle of inclination of the connecting member. Furthermore, a weight pivoted adjacent one end, as in the present embodiment of the invention if opposed directly by a spring is not moved 35 through equal radial distances by equal increases in the velocity of the rotating weight-driving member. However, by employing a flexible strip for connecting the centrifugally 40 actuated weight and the movable member, and by suitably designing both strip-guiding surfaces which progressively contact with the flexible strip and using a spring having a known constant, it is possible to modify the 45 force-transmitting action of the flexible strip to attain any desired differential ratio between the increments of increase of velocity of the rotating weight-driving member and the 50 increments of linear movement of the head 50 or of any motion responsive member or device carried or movable thereby.

In the illustrated embodiment of the invention, motion-responsive mechanism, described 55 hereinafter, in the form of a movable index needle (which here constitutes the ultimate responsive part) and its driving gearing, is connected to and actuated by the reciprocating head 50. Since it is desirable in speed-indicating apparatus that the index needle 60 shall cooperate with evenly spaced gradu-

tions on an indicating dial or chart, and further since gearing conveniently interposed between the indicating pointer and the reciprocating head usually exercises but little corrective effect upon the motion transmitted to the pointer, we deem it advantageous to dispose the curved strip guiding surfaces in such a way as to obtain substantially equal differential increments of movement of the head 50 for equal differential changes in rotary velocity of the weight-driving member 75 11.

However, since it is desirable for the purpose of preventing abrupt flexure of the flexible strip, as explained above, to employ curved strip-guiding surfaces at both ends of the strips, we preferably use these two curved strip-guiding surfaces (herein shown as the curved surfaces 59 and 60) for conjoint action in modifying the force-transmitting effect of the flexible strip 52. As 80 shown in Fig. 3a, the strip-guiding surfaces 59 and 60 are suitably curved and disposed with respect to the normal angularity of the flexible strips 52 and to the pivotal axes 29 85 of the weights to provide, within the range of movement of the pivoted weights, equal movement of the reciprocating head 50 for equal increases or decreases in speed of the rotating weight-carrying member. At zero velocity the weights 20-21 and head 50 are in the position indicated at V_0 and shown by full lines; when the shaft 12 is rotated at a speed of 1000 r.p.m., for example, the weights 20-21 under the action of centrifugal force 90 swing outwardly to force the head member 50 downwardly against the spring 51 into some such position, indicated at V_1 for example, and at a speed of 2000 r.p.m. the 95 weights and head are forced into a further position indicated, for example at V_2 , thus effecting equal linear movements of the head member for equal changes in the speed of the 100 rotating shaft and weight driving member.

Referring to Figs. 5 and 6 which illustrate 105 the invention as embodied in an instrument having a graduated dial and index needle, the instrument comprises a suitable casing 70 provided with a glass front 71 and mounted upon the upper extremity of the frame 17. 110 A dial 72 is disposed behind the glass cover 71, and an index needle 73 moves over suitable graduations 74 marked on the dial and preferably equally spaced to correspond to 115 equal changes in speed of the rotary weight-driving member 11, or shaft 12. The needle 73 may be actuated by usual gage movement parts, for example, an index staff 90 carrying a small pinion gear wheel 91 which meshes 120 with a sector gear 75 pivoted at 76 to any suitable fixed part of the mechanism such as the V-shaped frame member 78. An arm 77 connected to the sector gear 75, has an elongate slot 79 which receives an adjustable, 125 but normally fixed block 81. (Fig. 7.)

In the present embodiment of the invention we provide a flat spring 80 secured at one end by a screw 80^a (Fig. 7) to the arm 77 and block 81, and at its opposite end terminating in a knob-like part 83 which is disposed in an annular groove defined by spaced flanges 84 and 85 carried by the rotating and reciprocating head 50. The arm 77 and the head 50, it will be noted, are capable of movement in parallel planes, in the present instance, vertical. The spring 80 is capable of flexure in a vertical direction in the position of Fig. 6 and provides a considerable amplitude of flexible movement without undue friction with the reciprocating head. Rapid up and down movements of the reciprocating head 50 are effectively damped by the resiliency of this connection, and only the continued and major movements of the reciprocating head are transmitted through the spring 80 to the slotted arm 77 of the motion-responsive mechanism. This arrangement, wherein a resilient connection is employed between the reciprocating head and the motion-responsive mechanism, renders unnecessary the use of the conventional flywheel arrangement for damping the changes in rotary velocity of the weight-carrying member 11 or spindle 12, and likewise eliminates the torsional strains, the attendant friction, and the likelihood of injurious wear of parts caused by the use of a flywheel.

In the use of the complete device explained herein as an instance of our invention, the spindle 12 may be connected to any rotating part of which it is desired to measure the velocity. Rotation of the spindle 12 and hence of the weight-driving member 11 sets up a centrifugal force upon the weights 20 and 21 which together with the resilient force of the spring 51 determines the orbital path of the weights 20 and 21 at any given instant in their rotation. Changes in velocity of the spindle 12 and rotary weight-carrying member 11 bring about changes in the orbital path of the weights 20 and 21, components of the movement of the weights 20 and 21 being transmitted through the flexible strips 52, suitably modified by the curved strip-guiding surfaces 15, to the reciprocating head 50. From thence motion is transmitted through the resilient damping and connecting member 80 to the motion-responsive mechanism including the pointer 73 which, as explained above, may move over evenly spaced graduations to indicate the velocity of the moving part to which the device is connected.

The mechanism herein described is adapted for use in recording tachometers, double dial tachometers or combination recording and indicating tachometers.

It should be understood that the present disclosure is for the purpose of illustration only and that various changes in shape, pro-

portion, and arrangement of parts, as well as the substitution of equivalent elements for those herein shown and described, may be made without departing from the spirit and scope of the invention as set forth in the appended claims.

We claim:

1. A device of the class described comprising driving and driven members rotatable about the same axis and relatively movable along said axis toward and away from each other, one of said members having a part constructed and arranged to revolve in orbital paths determined by centrifugal force, means for yieldingly opposing relative movement of said members toward each other, a flexible strip connecting the revolving part with the other of said members to effect relative movement between said members in response to changes in the orbital path of said revolving part, an indicator having an actuating arm movable in a path substantially parallel to said axis, and resilient means for transmitting relative movement between said members to said arm, said means being capable of absorbing vibration set up in said members.

2. A device of the class described comprising means movable in response to centrifugal force along a substantially rectilinear path, means for yieldingly opposing such movement, an indicator having an actuating arm movable in a path substantially parallel to the path of movement of the responsive means, and resilient means for absorbing oscillations set up by said responsive means and for transmitting movement thereof to said arm.

3. A device of the class described comprising a rotary member having a pivotally mounted weight constructed and arranged to revolve in orbital paths determined by centrifugal force, a responsive member movable toward and away from said rotary member along its axis of rotation, means for yieldingly opposing movement of said responsive member toward said rotary member, means connecting said weight and responsive member for actuating the latter in response to changes in the orbital path of the former, indicating mechanism having an actuating member adjacent to the path of movement of said responsive member, and a resilient connection between said responsive member and said actuating member for transmitting movement of the former to the latter, said connection being capable of absorbing vibrations set up in said responsive member.

4. A device of the class described comprising a reciprocating head, centrifugally actuated rotary means for reciprocating said head in accordance with changes in rotary velocity of said means, indicating mechanism having an actuating member movable in a path adjacent to the path of movement of said head, and a spring connected to said

head and actuating member to transmit movement of said head to the actuating member while absorbing vibrations set up in said head.

5. A device of the class described comprising a rotating and reciprocating head having a peripheral groove concentric with its axis of rotation, centrifugally actuated rotary means for reciprocating said head in accordance with changes in rotary velocity of said means, indicating mechanism having an actuating member movable in a path substantially parallel to the path of movement of said head, a spring connected at one end to said actuating member, and means carried by the other end of said spring for engaging the groove in said head, whereby to transmit movement of said head to said actuating member.

10. A device of the class described comprising a rotary member having a pivotally mounted weight constructed and arranged to revolve in orbital paths in accordance with the centrifugal force acting thereon, a rotating and reciprocating head coaxial with said rotary member and having a peripheral groove concentric with its axis of rotation, a flexible strip connecting said weight and head, said weight having a curved surface of varying radius positioned progressively to contact with said flexible strip to effect reciprocating movement of said head in response to variations in rotary velocity of said rotary member, means for yielding opposing movement of said head toward said rotary member, indicating mechanism having an actuating arm movable in a path substantially parallel to the path of movement of said head, a spring connected at one end to said arm, and means carried by the other end of said spring for engaging the groove in said head, whereby to transmit movement of said head to said actuating arm.

7. In a tachometer of the class described, the combination of means movable along a substantially rectilinear path in accordance with different speeds of rotation of a driving member, an indicating mechanism having an actuating member movable in a path adjacent to said means, and resilient means for transmitting movement from said movable means to said actuating member while absorbing any vibrations set up in the former.

8. In a tachometer of the class described, the combination of a rotating member constructed and arranged to move axially in accordance with its speed of rotation, an indicating mechanism having an actuating member movable in a path substantially parallel to the path of movement of said rotating member, and a resilient connection between said rotating member and actuating member for transmitting axial movement of the for-

mer to the latter while absorbing any vibrations set up in the former.

9. In a tachometer of the class described, driving and driven members rotatable about the same axis and relatively movable along said axis toward and away from each other, one of said members having a pivotally mounted part constructed and arranged to revolve in orbital paths determined by centrifugal force, means for yieldingly opposing relative movement of said members toward each other, a flexible strip connecting said pivotally mounted part with the other of said members to effect relative movement between said members in response to variations in the orbital path of the former and guide means associated with said members having surfaces shaped and arranged progressively to contact with said flexible strip to effect equal changes in relative movement between said members for equal changes in their speed of rotation.

10. In a tachometer of the class described, a rotary member having a weight constructed and arranged to revolve in orbital paths determined by centrifugal force, a responsive member movable toward and away from said rotary member along its axis of rotation, means for yieldingly opposing movement of said responsive member toward said rotary member, a flexible strip connecting said weight and responsive member to effect movement of the latter in response to changes in the orbital path of the former, and guide means associated with said weight and responsive member having cooperating guide surfaces shaped and arranged progressively to contact with said flexible strip to effect equal changes in the movement of said responsive member for equal changes in the speed of rotation of said rotary member.

11. In a tachometer of the class described, a rotary member having a pivotally mounted weight constructed and arranged to revolve in orbital paths determined by centrifugal force, a rotating and reciprocating head movable toward and away from said rotary member along its axis of rotation, means for yieldingly opposing movement of said head toward said rotary member, and means for transmitting movement of said weight to said head in accordance with changes in the orbital path of said weight, said means comprising a flexible strip connected to said weight and head, and strip guiding means constructed and arranged progressively to contact with a greater length of said flexible strip as said weight revolves in progressively larger orbits to effect equal changes in movement of said head for equal changes in speed of said rotary member.

12. In a tachometer of the class described, driving and driven members rotatable about the same axis and relatively movable along said axis toward and away from each other,

one of said members having a part constructed and arranged to revolve in orbital paths determined by centrifugal force, means for yieldingly opposing relative movement of said members toward each other, and means for transmitting movement of the revolving part to the other of said members, said means comprising a flexible member connected to said part and to the other of said members, and guiding means constructed and arranged progressively to contact with said flexible member to effect equal changes in relative movement between said members for equal changes in their speed of rotation.
